UNITED STATES PATENT OFFICE.

WILLIAM J. PICKETT, OF WILKES-BARRE, PENNSYLVANIA.

KIT.

Application filed May 8, 1926. Serial No. 107,832.

This invention relates to a kit for mechanics and has relation more particularly to a device of this kind especially designed and adapted for use by persons engaged in the care of journals and journal bearings, air brakes and the like.

It is primarily an object of the invention to provide a device of this general character constructed in a manner whereby the various implements and material required by the workman are conveniently arranged and in a manner whereby the loss of tools and material is greatly reduced.

It is also an object of the invention to provide a kit of this kind comprising a container provided with a plurality of compartments each adapted to contain a special or particular material or fluid together with additional or supplemental containers each adapted to normally house or confine a desired tool or material as the work of the mechanic may require.

An additional object of the invention is to provide a device of this kind comprising a main container having supplemental containers therein together with means for supporting the main container in a tilted or inclined position to facilitate the filling of one of the supplemental containers.

The invention consists in the details of construction and in the combination and arrangement of the several parts of my improved kit whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in side elevation illustrating a kit constructed in accordance with an embodiment of my invention;

Figure 2 is a view in top plan of the structure as illustrated in Figure 1;

Figure 3 is a vertical sectional view taken substantially on the line 3—3 of Figure 2;

Figure 4 is a vertical sectional view taken substantially on the line 4—4 of Figure 2;

Figure 5 is a vertical sectional view taken substantially on the line 5—5 of Figure 2;

Figure 6 is a view in side elevation opposite to that illustrated in Figure 1;

Figure 7 is a horizontal sectional view taken substantially on the line 7—7 of Figure 1;

Figure 8 is a fragmentary vertical sectional view illustrating a portion of the means for normally supporting the torch;

Figure 9 is a view in side elevation of the kit as herein disclosed in a tilted or inclined position to facilitate the filling of a supplemental container.

As disclosed in the accompanying drawings, C denotes the main container having a conventional conical top 1 carrying a spout 2 whereby the contents of the container C may be readily discharged as required.

The spout 2 extends laterally beyond the container C the particular advantage of which being hereinafter referred to. The flow through the spout 2 is normally closed by a cap 3 threaded on the outer or free end portion thereof, said cap having engaged therewith, as at 4, an end portion of a flexible member 5, such as a chain, which is suitably anchored, as at 6, to the upper portion of the container C. By this means, loss of the cap 3 when removed is prevented.

The apex portion of the top 1 is open to provide a filling vent 7 for the container C, said opening or vent being normally closed by the cap 8. This cap 8 is provided with an outstanding knob 9 to facilitate this application or removal.

Arranged within the container C to one side of its center is a supplemental container 10 preferably cylindrical in form extending lengthwise of the container C. The end of the container 10 adjacent to the top 1 of the container C is closed with the opposite end open and said open end portion is coupled, as at 11, to the laterally directed branch 12 carried by the inserted end portion of a pipe 14 extending exteriorly of the container C at a point in close proximity to the bottom 15 of the container. The outer end of the pipe 14 is normally open but is closed by the cap 16, said cap having an outstanding knob 17 to facilitate its application or removal.

The extended or exterior portion of the pipe 14 carries and has in communication therewith a branch pipe 18 disposed in a direction toward the top 1 of the container C and coupled, as at 19, to the outer end portion of said branch pipe 18 is an elongated cylindrical member 20. The outer end of this member 20 is open but normally

closed by the cap 21, which also is provided with the knob 22 to facilitate its application or removal.

The central portion of the cap 21 is provided with an inwardly disposed tubular member or sleeve 23 in which is adapted to be forced an end portion of a brush handle 24. This handle 24 can also be readily removed from the member or sleeve 23. 5 This handle 24 is of such length that when the cap 21 is in applied position the lubrication brush 25 carried thereby will be disposed within the pipe 14. The container 10 is adapted to be initially filled with lubricating oil to be used on journals and journal bearings.

When it is desired to fill the supplemental container 10, the container C is tilted or inclined to a position particularly illustrated 20 in Figure 9 and at which time the outer or free end portion of the spout 2 serves as a supporting leg while the container C is held against lateral movement through the medium of a substantially U-shaped bracket B 25 the side members 26 of which being suitably attached to the peripheral wall 27 of the container C with the central part of the intermediate member 28 of the bracket also suitably secured to such wall 27. The intermediate member 28 of the bracket B is disposed substantially at right angles to the spout 2 with the spout 2 substantially central thereof.

The construction and mounting of the 35 supplemental container 10 is such that the feed therefrom is diametric in character with the oil in the pipe 14 maintaining a level free of the inner or inserted end of the brush handle 24 when the cap 22 is in applied position.

Also arranged within the container C is a second supplemental container 29 also arranged to one side of the axial center of the container C and which is adapted to hold 45 a supply of gasoline. The upper end of this supplemental container 29 is provided with a restricted neck 30 extending exteriorly of the container C through the top 1 thereof and having its outer end normally closed by 50 the removable plug 31, said plug having a wing head 32 to facilitate its removal or application. In communication with the lower portion of the supplemental container 29 is a pipe 33 extending exteriorly of the container C and having interposed in its 55 extended portion a controlling valve 34. Coupled to the pipe 33 outwardly of the valve 34 is a flexible tube 35. This tube is of desired length and leads to a torch T of any ordinary or preferred type and which, 60 in connection with the present kit, is particularly adapted to soften hard and frozen grease on a journal or otherwise as may be required.

65 The supplemental container 29 also has in

communication therewith a second pipe 36 extending exteriorly of the container C and in proper communication with the cylinder 37 of an air pump P arranged in relatively close proximity to the container C and further held thereto by a clamping member 38. 70

The tube 35 is coupled to the pipe 33 or more particularly the casing of the valve 34 by a removable coupling 39 so that when desired the torch T and its tubing 35 may 75 be entirely removed. Upon uncoupling of the tubing 35, the outer or free end of the pipe 33 is adapted to be closed by a plug 40. This plug when not in use is detachably engaged with the inserting end of the plug 80 31 as is particularly illustrated in Figure 5.

The connection between the tubing 35 and the torch T includes a handle member M which when the torch is not in use is adapted to be engaged between the spring arms 41 85 carried by an elongated plate 42. This plate 42 is slidably received between the guide flanges 43 carried by the peripheral wall 27 of the container C arranged exteriorly thereof.

The portion of the handle member M in relatively close proximity to the torch proper constitutes a reduced part or shank 44 which is received between the outstanding parallel arms 45 arranged at the upper portion of the plate 42 and said arms provide additional means for supporting the torch T when not in use. The plate 42 may be readily removed from the container C when desired but when in applied position its lower or inner end 100 has direct contact with an outstanding flange 47 carried by the lower end of the plate 42 thus limiting the extent of movement of the plate inwardly of the guide flanges 43. When the torch is in supported engagement 105 with the plate 42 the tubing 35 is preferably disposed around the pump P as illustrated in Figures 1 and 9 over the outstanding hook members 48 carried by the auxiliary containers 49 and 50 and below the knob 17 of the 110 cap 16. As is particularly illustrated in Figure 7, the pipe 14 is arranged substantially midway between the auxiliary containers 49 and 50.

The auxiliary containers 49 and 50 are attached or anchored to the container C by the interposed arms 51 with said auxiliary containers in close proximity to the container C.

The auxiliary container 49 has arranged therein the receptacle 52 which is adapted to hold a supply 53 of waste. The peripheral wall of the applied receptacle 52 is spaced from the peripheral wall of the auxiliary container 49 providing a space in which may be stored or housed a stencil or the like as indicated at 54 by broken lines. The upper end of the container 49 is open but is adapted to be closed by the removable top 55 conical in form and having its apex portion provided with a tubular extension 56. When the 130

top 55 is removed it can, upon reversal, be readily employed as a funnel. The bore through the extension 56 is normally closed by the cap 57 engaged with the outer or free end thereof and coacting with said cap 57 and extension 56 is a flexible member 58, such as a chain, operating to prevent loss of the cap 57 when removed.

An oil can D is adapted to be housed or confined within the top 55 and the spout 59 thereof, as is illustrated in Figure 5, is adapted to be threaded with the inner portion of the bore of the extension 56 whereby the can D is effectively held within the top 55. The spout 59 is carried by a cap 60 detachably engaged with the body 61 of the can D to permit the can to be readily filled with the desired liquid. In practice, it has been found of advantage to fill this body 61 with kerosene so that when removing nuts or the like from journal boxes a sufficient quantity of kerosene may be applied thereto to facilitate removal and thus greatly reduce waste of the kerosene. This also avoids the necessity of the workman or mechanic carrying along a separate can of kerosene for this purpose as is now required and which results in frequent loss of can together with loss of kerosene due to such cans being knocked over.

There is adapted to be housed within the body 61 of the can D a paint brush 62 which is detachably engaged, as at 63, with the inner portion of the spout 59 and preferably through the medium of a shank threaded therein. It is to be understood that when the can is to be employed in the application of kerosene or other oil, the brush 62 is removed but when the brush is to be employed the cap 60 is freed from the body 61 and the spout 59 employed as an operating handle. This brush 62 may be employed for any purpose desired.

The auxiliary container 50 is adapted to house an oil swab S which comprises, as herein disclosed, a hollow conical member 64 provided at its apex portion with a knob 65 whereby the same may be readily manipulated. Extending inwardly of the conical member 64 from its smaller or apex end is a shank 66 to the free end portion of which is detachably connected a disk 67 the periphery of which is toothed or otherwise roughened. This disk 67 is arranged in the central portion of a suitable quantity of waste 53' and when the disk 67 is engaged with the shank 66 such waste is effectively maintained within the member 64. When the swab S is placed within the auxiliary container 50, the waste is preferably downwardly disposed so that kerosene admitted within the container 50 may operate to cleanse the waste. When it is desired to drain the kerosene from within the container 50, the plug 68 is removed from the outlet

nipple 69 in communication with the lower portion of the container 50. The container 50 is in communication through the pipe 70 with the interior of the container C and interposed in said pipe 70 is a controlling valve 71. Upon opening the valve 71 the requisite supply of kerosene within the container C will be delivered within the auxiliary container 50 whereupon the valve 71 will be adjusted to closed position.

The upper end of the container 50 is also open but is adapted to be normally closed by the conical top 72 provided at its apex portion with a knob 73 for properly handling the same.

Extending within the top 72 from the apex end thereof is a shank 74 with which is detachably engaged the knob 75 carried by a cap 76. This cap 76 is adapted to close the open end of a can body 77 of a structure similar to the can body 61 hereinbefore referred to. This can body 77 is adapted to contain a supply of paint such as may be required for use in connection with a stencil 54 although, if desired, other liquid may be stored therein.

The cap 76 at its axial center is provided with an inwardly disposed tubular shank 78 with which is detachably engaged an outstanding shank 79 carried by the head of a stenciling brush 80. The brush 80 can be readily removed when desired but when in use the knob 75 constitutes a handle therefor.

The containers 49 and 50 are connected by the reinforcing or bracing members 81 and to one of which is adapted to be removably engaged a grease pot G, said grease pot being comprised in the kit when especially used by an air brakeman. The pot has attached to its peripheral wall a clip 82 whereby said pot G may be readily applied as is illustrated in Figure 3 of the accompanying drawings. This pot G has its upper end open which is adapted to be normally closed by a cap 83 provided with a handle knob 84. At its axial center the cap 83 is provided with an inwardly disposed tubular shank 85 with which is engaged an end portion of a paddle 86 for use in properly handling the grease. The inner or connected portion of the paddle 86 has slidably engaged thereon a cup-like member 87 in which is adapted to be housed a coil 88 of wire, such wire being particularly adapted for use by an air brakeman in cleaning out a retaining valve or otherwise as may be required. Normally the member 87 is in close contact with the cap 83 as is illustrated in Figure 3.

Extending within the container C at opposite sides of its axial center and through the top 1 thereof are the cylindrical housings 89 and 90. Each of these housings extends above the top 1 and exteriorly thereof and has its upper open end normally closed

by a cap 91 provided with an operating knob 92. The cap 91 associated with the housing 89 has secured at the axial center of its inner face a bearing scraper X while the cap 91 associated with the housing 90 has secured to the axial center of its inner face the file Y. These two implements are essential to a mechanic working on journal bearings of railway rolling stock and the like and by providing the housings 89 and 90 provision is made whereby such tools are at hand when desired yet readily out of the way when not in use.

The top 1 of the container C is also provided with a housing 93 partially extending within the container C and which is adapted to hold a supply of matches, the outer or upper end of this housing 93 being open but normally closed by the cap 94, said cap being provided with a knob 95 to facilitate its removal or application.

The housing 89 is adapted to have placed therein a suitable length of emery cloth and the handle member M is operatively engaged with the upper portion of the container C to provide means whereby the kit may be readily and conveniently carried.

From the foregoing description it is thought to be obvious that a kit constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A kit comprising a container, a spout communicating with the interior of the con-

tainer through the top side thereof and having a pouring end disposed beyond the vertical side thereof and a bracket attached to said vertical side at the lower portion of the container, said spout and said bracket serving as means for holding the said side of the container in an inclined position.

2. A kit comprising a container, a spout communicating with said container at the upper portion thereof and extending to one side thereof, a bracket supported at the lower portion of the said container, said spout and bracket providing means for holding the container in an inclined position, a supplemental container housed within the first mentioned container and having an extension disposed exteriorly of the first mentioned container, the outer end of said extension being open, and means for sealing said open end, said open end being upwardly disposed when the first mentioned container is supported in an inclined position.

3. A kit comprising a container, a spout in communication with said container at the upper portion thereof and extending to one side thereof, a bracket supported at the lower portion of the container, said spout and bracket serving as means for holding the container in an inclined position, a supplemental container housed within the first mentioned container and having an extension disposed exteriorly of the first mentioned container, the outer end of said extension being open, means for sealing said open end, said open end being upwardly disposed when the first mentioned container is supported in an inclined position, the exterior portion of the extension of the supplemental container being provided with an upstanding branch and a removable closure member for the outer end of said branch.

In testimony whereof I hereunto affix my signature.

WILLIAM J. PICKETT.
